UNITED STATES PATENT OFFICE.

JOHN R. SUMAN, OF HOUSTON, AND ADRIAN R. GAMBLE, OF VELASCO, TEXAS.

HOISTING DRUM.

1,414,795.

Specification of Letters Patent. Patented May 2, 1922.

Application filed October 25, 1920. Serial No. 419,305.

To all whom it may concern:

Be it known that we, JOHN R. SUMAN and ADRIAN R. GAMBLE, citizens of the United States, residing, respectively, at Houston, 5 Harris County, Texas, and Velasco, Brazoria County, Texas, have invented a certain new and useful Improvement in Hoisting Drums of which the following is a full, clear, and exact description, such as will enable others 10 skilled in the art to which it appertains to make and use the same.

Our invention relates to an improvement in hoisting drums. It pertains particularly to drums for use on draw works employed 15 in the rotary system of drilling oil, gas, and water wells.

In the present system of rotary drilling used in the oil fields, a draw works is employed to raise and lower the drill stem and 20 the drill, the casing, and other apparatus in the well. A cable for this purpose is operated from a power actuated hoisting drum located on a derrick platform. The cable passes upwardly from the hoisting 25 drum over pulleys on the crown block at the top of the derrick and downwardly around sheaves in the traveling block and again over similar sheaves on the crown block and passes thus back and forth from the traveling 30 block to the crown block and finally back down to the derrick platform where the lower end of same is attached to beams supporting the platform. This lower outer 35 end of the cable is called the dead line and does not assist in any way in the raising and lowering of the load. The entire cable is wound upon the one hoisting drum ordinarily employed. When large loads are to be handled in deep wells, it is common to 40 pass the cable back and forth from the crown block to the traveling block 4 or 5 times so as to make 8 or 10 lines between the two blocks so as to increase the power in raising the load. The operation of the drum in 45 raising the load is hence slow and a heavy load pulls upon the cable as it is wound up on the drum. In reeling up the cable it is found that, after the first layer has been wound upon the drum the tightness of the 50 cable due to the load thereon often causes a cutting of cable already wound until it is weakened or broken so that it has to be repaired or a new cable used.

It is also necessary when a light load is 55 being operated and speed is desired to unthread the cable from the crown block to

the traveling block so as to reduce the number of strands of cable between the two blocks so as to increase the speed of hoisting the load. When, however, the load increases, it becomes necessary to rethread the cable through the two blocks, so as to increase the number of strands between the two, and thus give more power to the drum at the sacrifice of speed of operation. It 60 sometimes becomes necessary to do this while the drill stem is in the well and there is then danger that so much time will be consumed in re-arranging the cable that the drill stem will become frozen in the well 65 and cannot be withdrawn, thus junking the well.

The object of our invention is to employ a plurality of hoisting drums upon the same shaft so that the cable may be wound partly 70 on one drum and partly on another so that the danger of cutting the cable will be greatly lessened.

Another object is to provide an arrangement of hoisting drums whereby the cable 75 may be wound from both ends at once, if desired, so as to double the speed by which the load is operated.

Another object is to so arrange the double hoisting drum that one drum may be operated independently of the other and whereby, due to the arrangement of the apparatus, the two drums may be operated simultaneously when desired.

The further objects and advantages of our 90 invention will more clearly appear in the specification which follows.

Referring to the drawing forming a part of this specification and wherein like numerals of reference are applied to both the views, Fig. 95 1 is a central longitudinal section through a derrick upon which is mounted a preferred embodiment of our invention, and showing the same in side elevation; and Fig. 2 is an enlarged central longitudinal section 100 through the hoisting drum shown in Fig. 1.

In Fig. 1 is shown a broken view of a derrick 1 being mounted upon a base 2, and having a platform 3 thereon, on which is mounted the hoisting apparatus A, ordinarily used in drilling operations. At the upper end of the derrick is mounted a support 4 sustaining the crown block 5 resting thereon. This crown block comprises a series of pulleys or sheaves 6 mounted upon bearing shafts 7 resting upon the block 5. The pulleys 6 are formed with a peripheral

groove, in which the cable 8 is adapted to run. These sheaves may be of any desired number, usually from 2 to 6, said pulleys being mounted in rows upon the supporting frame of the crown block 5 so that the cable may pass over each of the pulleys in turn without the cable interfering with the operation of any of the separate pulleys. Below the crown block is a traveling block 9. This traveling block is nothing more than a compound pulley, or system of sheaves mounted in a frame work 10, said frame work acting as a support for the sheaves and extending a short distance below the same for attachment to a yoke 11 and hook 12, to which the bail 13 of the swivel 14 is attached. The swivel 14 acts as a non-rotatable support for the rotating drill stem 15, to which the drill, not shown, is attached. This swivel, drill stem and drill constitute the ordinary load in the regular drilling operation. It will be understood, however, that the hook 12 may be attached to an elevator for raising and lowering casing, fishing tools and other apparatus ordinarily in use about the derrick in drilling operations.

The hoisting apparatus A which we employ is mounted upon the derrick platform. A cross shaft 15 is mounted for rotation in bearings 16 secured to uprights 17 upon the platform. The shaft 15 is operated preferably by some source of mechanical power by means of a sprocket wheel 18 mounted upon the shaft toward one end thereof. This sprocket wheel is mounted loosely for rotation on the shaft under ordinary circumstances, but has a projecting hub on the outer face thereof having teeth 19 adapted to mesh with teeth 20 upon the clutch member 21, the said clutch being keyed slidably to the shaft 15 and operated by means of a lever 22 in a well known manner. Thus the shaft may be operated through the means of the sprocket wheel 18 by simply throwing the clutch 20 into mesh with the teeth on the hub of the sprocket wheel. Adjacent the sprocket wheel on the side opposite the clutch is a hoisting drum 23. This drum is of ordinary construction and, as shown in Fig. 2, is secured to the shaft by means of a key 24 thereon. The end adjacent the sprocket wheel 18 is provided with a brake drum 25, over which a brake band 26 operates, the said brake band being tightened upon the drum by means of a lever 27.

Immediately adjacent the drum 23 is another drum 28. This drum, as shown in Fig. 2, is mounted idly on the shaft 15 for rotation thereon and for this purpose is provided with bushings 29 and 30, these bushings being of any preferred bearing metal, such as bronze, etc. The outer periphery of the drum, which, in both the hoisting drums, is separated from the shaft

by means of metal discs 31 at the ends thereof, is made up of a cylindrical length of metal pipe 32 furnishing a surface upon which the cable is mounted. Between the pipe 32 and the shaft, intermediate the ends, 70 is a chamber 33 which we contemplate using as a reservoir for lubricant and, as a means of filling this chamber from time to time, we have provided an inlet pipe 34 having a closing cap 35 at the outer end thereof. 75 The outer end of the drum 28 has a brake drum 36 thereon, by means of which the speed of the drum may be controlled. Teeth 37 on the outer face of the hub of the drum are adapted for co-operation with the teeth 80 38 of a clutch 40 keyed slidably to the shaft by means of a key 39. The clutch 40 is operated by means of a hand lever 41, pivoted on a bracket 42 secured to one of the uprights 17. 85

The operation of our device will now be clear. The cable will be wound from the drum 23, upwardly over one of the sheaves 6 of the crown block and back through corresponding sheaves in the traveling block 9 90 and again over another sheave in the crown block, thus passing back and forth from the crown block to the traveling block so as to provide the customary 8 lines used in heavy loads. The forward end of the cable will 95 then be passed downwardly around the second drum 28.

When light loads are being operated and speed is desired, both drums will preferably be operated. For this purpose, the brake 100 band will be loosened and the clutch 20 will be thrown into gear with the power operated sprocket wheel 18. This will rotate the shaft and the drum 23 fixed thereon. The clutch 40 will then be also thrown in, the 105 brake band on the drum 36 being loosened and the hoisting drum 28 thus operated. The rotation of the shaft 15 will draw upon both ends of the cable at once and, as will be obvious, the speed with which the load 110 is handled will be doubled. It is apparent, of course, that if less than the usual 8 lines are threaded from the crown block to the traveling block the speed may be still further increased. 115

When the load becomes so heavy, however, that it can not be easily handled by the ordinary power applied to the shaft 15, the clutch 40, serving to cause the operation of the drum 28 will be thrown out of gear and the brake band on the drum 36 tightened so as to prevent the rotation of this drum. The rotation of the shaft 15 will then act to operate the drum 23 only and the speed of handling the load will be only one-half as 125 great as when both drums were used. The power, as will be obvious, will be increased by two. Thus, without the necessity of re-threading the cable over the crown and traveling block, the power will be increased 130

when the load becomes heavy. The further advantage will arise in that part of the cable may be wound up on the drum 28 and when the load is raised by the operation of the 5 cable on the drum 23 only the necessary cable used in operating the load will be wound upon the drum 23, and the liability of cutting and increased wear on the cable will be greatly lessened.

10 Having thus described our invention, the advantages of which will be understood to one skilled in the art, what we claim as new and desire to protect by Letters Patent is:

1. In a device of the character described, 15 a compound hoisting drum, comprising a shaft, a power operated wheel thereon, a clutch to throw said shaft in and out of gear with said wheel, a main drum secured to said shaft, a second drum on said shaft 20 and normally idling thereon, hand operated means to connect said second drum to said shaft, a load-sustaining cable having operative connection with both of said drums and means to control the speed of said drums.

25 2. In a device of the character described, a compound hoisting apparatus comprising, a rotatable shaft, means to connect and disconnect said shaft to source of power, a main drum fixed on said shaft, a second drum, 30 normally idling on said shaft, a load-sustaining cable having operative connection with both of said drums, and means to connect said second drum to said shaft as desired, whereby said cable may be reeled or unreeled from either or both drums simultaneously, as described.

3. In a device of the character described, 35 a compound hoisting apparatus comprising

a rotatable shaft, a clutch adapted to connect said shaft to a source of power, a cable 40 drum fixed on said shaft, a second drum normally idling on said shaft, means to connect said second drum to said shaft, a load-sustaining cable having operative connection with both of said drums and brakes controlling the speed of each of said drums. 45

4. In a device of the character described, a derrick, a load operating means comprising a crown block on said derrick, a traveling block attached to said load, a hoisting apparatus having two drums, means for rotating one or both of said drums, and a cable secured to one of said drums, passed over said crown block and around said traveling block a plurality of times, and secured at the 55 other end to the other of said drums, whereby said cable may be reeled from one end or from both ends at once as desired.

5. In a device of the character described, a derrick, a hoisting apparatus comprising 60 a crown block, a traveling block, a rotatable shaft, two cable drums thereon, means to rotate one of said drums independently of the other and means whereby both may be rotated simultaneously as desired, and a 65 cable secured at its ends to said drums, the intermediate portion being passed over said crown block and said traveling block a plurality of times in the manner and for the purpose described. 70

In testimony whereof, we hereunto affix our signatures this the 5th day of October, A. D., 1920.

JOHN R. SUMAN.
ADRIAN R. GAMBLE.
